F. O. GRAY

TAXIMETER FLAG CONTROL

Filed May 12, 1923

UNITED STATES PATENT OFFICE.

FREDERICK O. GRAY, OF DAYTON, OHIO, ASSIGNOR TO OHMER FARE REGISTER COMPANY, A CORPORATION OF NEW YORK.

TAXIMETER-FLAG CONTROL.

Application filed May 12, 1923. Serial No. 638,456.

To all whom it may concern:

Be it known that I, FREDERICK O. GRAY, a citizen of the United States, residing in the city of Dayton, county of Montgomery, 5 and State of Ohio, have invented certain new and useful Improvements in Taximeter-Flag Controls, of which I declare the following to be a full, clear, and exact description.

10 This invention relates to a device for effecting the complete movement of a control shaft having a plurality of significant positions to another of such positions when it has been slightly displaced from its first 15 significant position. The invention is shown as applied to a taxicab fare register device, or taximeter. The purpose of these machines is to register and indicate the fare due from the passenger according to the 20 distance traveled and the time consumed in waiting, or while the vehicle is traveling under a predetermined speed. The taximeter usually includes also various auxiliary mileage and time counters. It is customary 25 in these machines to provide a control shaft for effecting such functions as connecting and disconnecting the fare registering devices, the mileage counting devices and the time counting devices with their actuating 30 mechanisms, and such other incidental functions as may be found necessary. The control shaft is extended at one or both ends outside the casing of the machine and carries at one end a flag or suitable signal 35 which indicates by its position whether or not the machine is registering, and the character of the registrations being effected. Incidentally the flag indicates to the public by its position whether or not the vehicle is 40 "For hire." Since the control shaft effects certain operative relations, as already stated, and is designed to indicate by the position of its flag the operation being carried out by the machine, the shaft and its flag have 45 definite positions of certain significance, and it becomes important that they be definitely located in these significant positions and not permitted to occupy any improper intermediate positions, under which circumstance 50 it would be impossible to ascertain with any degree of certainty in what way the taximeter was functioning.

The object of this invention is, therefore,

to provide devices associated with such a control shaft which will become effective 55 when the shaft is slightly displaced from one significant position to effect its complete movement to a second significant position.

A further object of the invention is to 60 provide, associated with the control shaft, a cam which will serve the double function of locating the shaft in its initial position and of effecting its movement to a second position when it is slightly displaced from 65 its initial position.

A further object of the invention is to 70 provide a device auxiliary to the cam device above described and tending to effect the same operation.

A further object of the invention is to 75 utilize, for the purpose outlined, certain elements already present within the machine.

A further object of the invention is to 80 adapt the devices provided for the purpose outlined, to go within the casing at present used on a certain type of taximeter without displacing other necessary parts of the machine.

More specifically, my invention is shown 85 as applied to a taximeter of the type described in Patent 1,186,164 of April 20, 1915 to J. F. Ohmer et al., and Patent 1,182,408 of May 9, 1916 to J. F. Ohmer et al. The taximeter therein described comprises three series or banks of counters. The first of 90 these are visual counters including a fare counter and an extras counter. The fare counter is adapted to be driven an amount proportional to the distance traveled or to the time consumed in waiting. The extras counter is operated manually by the driver. The second series of counters are adapted 95 to print on a ticket to be issued to the passenger the amount payable for fare and extras, the number of the ticket and certain identification data. The third series of counters are adapted to print a record and 100 include beside the counters in the first two series, certain mileage and time counters the operation and functions of which are fully described in the patents above identified.

In the drawings Fig. 1 shows an end 105

elevation of so much of the Ohmer taximeter as is necessary to illustrate the application of my invention thereto. Fig. 2 is a fragmentary elevation showing the flag shaft and cams thereon in the position they occupy when the machine is in hire. Fig. 3 is a front elevation of the device constituting my invention and so much of the taximeter as is necessary to illustrate the attachments thereto.

The shaft 20 is adapted to be driven from the ground wheel of the vehicle. This shaft carries two worms 21 and 22, meshing respectively with gears 23 and 24 loosely mounted on studs carried by the frame plate 25. These studs also carry intermeshing gears 26 and 27 adapted to be driven from the gears 23 and 24, by one way ratchet and pawl mechanisms fully described in Patent 1,136,164 above cited. A gear 28 mounted on a stud 29 in an arm 30 is adapted to mesh with the gear 27. Rigid with the gear 28 is a pinion 30 which is in mesh with a gear 31 loosely carried on a shaft 32. This gear 25 drives the shaft 32 by a ratchet and pawl mechanism fully described in pending application 587,219 filed September 9, 1922. The clock mechanism is indicated generally by 33. The way in which the various counters contained in the machine are driven and the details of these counters form no part of the present invention. It is sufficient to say that all fare counting devices are actuated from the shaft 32, that all mileage counting devices are actuated from gear 26 and that all devices moved proportional to elapsed time are actuated from the clock mechanism.

For the purpose of swinging the gear 28 into and out of mesh with gear 27, the arm carrying this gear is pivoted on shaft 32 and is extended upwardly and rearwardly from said shaft, its upper end engaging the periphery of a cam 34 on the control shaft 35, said arm being held in engagement with said cam by spring 36. An arm 38 also controlled by cam 34 acts to start and stop the clock at the proper times. Various other functions are performed by the control shaft 35, which shaft is extended through the case of the machine and carries at its end the signal 39 which indicates by its position whether or not the machine is registering, and if registering, what the character of the registration is. To locate the shaft 35 in its initial or "For hire" position, a cam 40 is fixed thereon. Engaging the periphery of this cam is a roller 41 carried by an arm 42 pivoted at 43 to the frame plate 25, and pressed against the periphery of the cam 40 by a stout spring 44. A slight depression 411 in the periphery of this cam, clearly illustrated in Fig. 2, is occupied by the roller 41 when the flag is in "For hire" position (Fig. 1) and serves

to locate the flag and the control shaft in this position. When the central shaft is slightly displaced from "For hire" position by movement of the flag or signal 39, the roller 41 leaves the depression 411, and by 70 its engagement with the inclined surface 45, tends to force the control shaft toward its second position, in which position the roller occupies the depression 46. The depression 411 and the incline 45 are so related that 75 roller 41 engages the incline 45, and spring 44 thus tends to move the flag to "Hired" position after a very short movement of the flag 39. This characteristic is of great importance, for as long as the roller 41 engages surface 411 the spring 44 tends to restore the flag to "For hire" position, instead of forcing it toward "Hired" position. Moreover the flag or control shaft 35 is usually provided with some form of "full stroke" 80 device which prevents retrograde movement thereof prior to the completion of the forward stroke. Thus, if the spring 44 draws the flag toward "For hire" position, and the full stroke device prevents such movement, 85 the flag may be retained indefinitely in some intermediate position, and the correct functioning of the meter thus defeated. This is a defect which is inherent in all the taximeters prior to my invention of which 90 I am aware.

The construction of other parts of the taximeter may limit the size of cam 40, and thus the effectiveness of spring 44 in rotating control shaft 35. To insure that 100 flag 39 and shaft 35 will move to "Hired" position without stopping in an intermediate position the following auxiliary mechanism is provided.

The control shaft 35 carries a mutilated 105 gear 47 adapted to mesh with a sector gear 49 carried by the printer shaft 48. By means of these gears the control shaft is restored to initial position near the completion of the printing operation, as fully 110 explained in the aforementioned Patent 1,182,408, to Ohmer et al. For the purpose of assisting in automatically moving the control shaft to its second position when it is slightly displaced from 115 its initial position, a link 50 is pivoted to the mutilated gear 47 at 51. To the free end of this link is attached a spring 52, the opposite end of this spring being attached to the base plate of the machine at 53. The link 50 is slightly curved to pass the control shaft 35, and its point of attachment 51 to the mutilated gear is so located that when the control shaft is in initial position the point of attachment 51, the control shaft 120 35, and the fixed end of the spring 53 are in line. In this "dead center position" it is apparent that the spring 52 has no tendency to rotate the control shaft 35. However, as soon as the control shaft is slight- 125 65 130

ly displaced, the spring 52 becomes effective, assisting spring 44 in promptly moving the control shaft to its second position. The correct movement of the control shaft is thus assured.

I do not intend that this invention shall be construed as limited to the precise structure herein described and illustrated in the drawings, but wish it to be construed to 10 cover all equivalent devices falling within the scope of the appended claims.

I claim:

1. In a taximeter, a control shaft having a plurality of significant positions, a device 15 effective on a slight movement of said shaft from its first position to complete its movement to another position, said device comprising a cam and a spring pressed actuator therefor, and a second device auxiliary to 20 said first device comprising a spring drawn link.

2. In a taximeter, a control shaft having a plurality of significant positions, and a device effective on a slight movement of 25 said shaft from its first position to complete its movement to another position.

3. In a taximeter, in combination, a control shaft having a plurality of significant 30 positions, a signal attached thereto and serving as a manual operating means therefor, and means effective on a slight initial movement of said shaft from its first position by manipulation of said signal to complete its movement to its second position, said means comprising in part a cam on said control 35 shaft, and a spring pressed arm operative on said cam.

4. In a taximeter in combination, a control shaft having a plurality of significant 40 positions, a signal attached thereto and serving as a manual operating means therefor, a locating device adapted to complete the movement of said shaft from its initial position to its second position and to yieldingly retain said shaft in its significant 45 positions, means independent of said signal for returning said control shaft to its initial position, and means auxiliary to said movement completing and locating device associated with said returning means.

5. In a taximeter, in combination, a control shaft having an initial position and a second significant position, a device comprising a cam tending to complete movement 55 of said control shaft, a second device auxiliary to the first device and comprising a disk on said control shaft, a pin eccentrically placed in said disk, a connecting link mounted on said pin, and a

spring attached to the free end of said link and to the machine frame.

6. In a taximeter, in combination, a control shaft having an initial position and other significant positions, a device for completing movement of said shaft to its second position comprising a crank device on said shaft, a link pivoted thereto and a spring tensioned between the free end of said link and the machine frame, the point of attachment of the spring to the frame 65 being such that when the control shaft is in initial position the control shaft, the crank and link are in "dead center" relation.

7. In a taximeter, in combination, a control shaft having an initial position and other significant positions, a device comprising a cam for moving said shaft to its second position when slightly displaced from initial position, the configuration of the cam rendering said device ineffective 75 when said shaft is in initial position, an auxiliary crank and connecting link device also tending to move said shaft to its second position but in "dead center" position when said shaft is in initial position.

8. In a taximeter, a control shaft having an initial position and other significant positions, a cam on said shaft, a spring pressed arm, a roller on said arm acting on the periphery of said cam, the configuration of said cam being such that said spring maintains said cam and shaft in initial position but when they are slightly displaced from initial position completes their movement to a second significant position.

9. In a taximeter, a control shaft having an initial position and other significant positions, a cam on said shaft, a spring pressed arm, a roller on said arm acting 90 on the periphery of said cam, the configuration of said cam being such that said spring maintains said cam and shaft in initial position but when they are slightly displaced from initial position completes 95 their movement to a second significant position, a disk on said shaft, a stud eccentrically placed on said disk, a link pivoted to said stud, and a spring tensioned between the free end of said link and the machine 100 frame, the point of attachment to the frame being so located that when the shaft is in initial position the stud is in alignment with the said point of attachment and the center of the shaft.

In testimony whereof I affix my signature.

FREDERICK O. GRAY.
